(57) **CLAIM**

The ornamental design for a hair-care applicator for use with a spray can, as shown and described.

DESCRIPTION

FIG. 1 is an isometric view of a first embodiment of a hair-care applicator;

FIG. 2 is a reverse-angle isometric view of FIG. 1;

FIG. 3 is a front view of FIG. 1;

FIG. 4 is a back view of FIG. 1;

FIG. 5 is a left view of FIG. 1;

FIG. 6 is a top view of FIG. 1;

FIG. 7 is a bottom view of FIG. 1;

FIG. 8 is an isometric view of a second embodiment of a hair-care applicator;

FIG. 9 is a reverse-angle isometric view of FIG. 8;

FIG. 10 is a front view of FIG. 8;

FIG. 11 is a back view of FIG. 8;

FIG. 12 is a left view of FIG. 8;

FIG. 13 is a top view of FIG. 8;

FIG. 14 is a bottom view of FIG. 8;

FIG. 15 is an isometric view of a third embodiment of a hair-care applicator;

FIG. 16 is a reverse-angle isometric view of FIG. 15;

FIG. 17 is a front view of FIG. 15;

FIG. 18 is a back view of FIG. 15;

FIG. 19 is a left view of FIG. 15;

FIG. 20 is a top view of FIG. 15;

FIG. 21 is a bottom view of FIG. 15;

FIG. 22 is an isometric view of a fourth embodiment of a hair-care applicator;

FIG. 23 is a reverse-angle isometric view of FIG. 22;

FIG. 24 is a front view of FIG. 22;

FIG. 25 is a back view of FIG. 22;

FIG. 26 is a left view of FIG. 22;

FIG. 27 is a top view of FIG. 22; and,

FIG. 28 is a bottom view of FIG. 22.

The broken lines are directed to environment and are for illustrative purposes only; the broken lines form no part of the claimed design.
